United States Patent Office.

JAMES H. HULSE, OF BALTIMORE, MARYLAND.

Letters Patent No. 76,919, dated April 21, 1868; antedated April 8, 1868.

IMPROVEMENT IN FRAMES FOR STRETCHING PANTS.

The Schedule referred to in these Letters Patent and making part of the same.

TO ALL WHOM IT MAY CONCERN:

Be it known that I, JAMES H. HULSE, of the city of Baltimore, in the State of Maryland, have invented a new and useful Machine for Pressing Pants; and I do hereby declare that the following is a full and exact description thereof, reference being had to the accompanying drawing and to the letters of reference marked thereon.

The nature of my invention consists in a novel arrangement of pants on a frame for stretching pants, and it consists in two upright stays, marked *a b c*, the stays *b c* hinged, to permit them to expand, in connection of openings mortised in the said stays *a b c*. Stretchers *d* and *f* pass through the upright stays at the top and bottom, by means bottoms of the pants. Stretcher *e* works in the groove *h*, for the purpose of expanding the seat and legs of the said pants.

The stretchers *d* and *f* are kept in place by means of pins *g*, as shown in the drawings, passing through the said stretchers *d* and *f*, the whole machine pressing and stretching the said pants.

Now, having described the nature of my invention, what I claim as new, and desire to obtain by Letters Patent, is—

The combination of the upright, *a*, with cross-supporting piece *e*, with the hinged stretcher *b c*, and adjustable supporting cross-pieces *f d*, the whole arranged as herein described, and for purpose specified.
